UNITED STATES PATENT OFFICE

HOMER C. BENNER, OF LANCASTER, PENNSYLVANIA.

STORM-APRON FOR VEHICLES.

No. 824,774.

Specification of Letters Patent.

Patented July 3, 1906.

Application filed July 29, 1905. Serial No. 271,772.

To all whom it may concern:

Be it known that I, HOMER C. BENNER, a citizen of the United States, residing at Lancaster, in the county of Lancaster and State of Pennsylvania, have invented certain new and useful Improvements in Storm-Aprons for Vehicles, of which the following is a specification, reference being had therein to the accompanying drawings.

This invention relates to improvements in that class of aprons designed to protect the occupants of vehicles; and the objects of the invention are, first, to secure the inner edge of the apron in an elevated position and so that said edge need not be detached from its supports when either one or both sides thereof are moved forward to allow of ingress to and egress from the vehicle; second, to prevent accidental movement by the wind of the elevated inner edge of the apron when in a backward or forward position; third, to construct the apron so that it may be adapted to fit snugly over dashboards of different lengths, and, fourth, to prevent entrance into the vehicle of rain or snow through the slot in the apron through which the driving-reins pass. I attain these objects by the mechanism illustrated in the accompanying drawings, which form a part of this specification, and in which—

Figure 1 is a front perspective view of the forward part of a vehicle having an apron attached thereto embodying my invention, the apron being raised and the top of the vehicle removed. Fig. 2 is a similar view, but with one side of the inner edge of the apron pushed forward to allow of ingress and egress. Fig. 3 is a perspective view showing the manner of securing a guide-rod to a top rail of a vehicle having an inside covering for the bows. Fig. 4 is an elevation of the inside of the dashboard, showing the manner of securing the apron thereto; Fig. 5, a transverse vertical section of the dashboard and of the front of the apron; Fig. 6, a perspective view of one end of the dashboard with a portion of the front of the apron free from the fastening-strap and turned back; Fig. 7, a horizontal section of one end of the dashboard and of the portion of the curtain attached thereto; Fig. 8, a front perspective view of the part of the curtain having therein the slot through which passes the driving-reins and of the

shield covering said slot, and Fig. 9 a transverse section on broken line A of Fig. 8.

Similar numerals indicate like parts throughout the several views.

Referring to the details of the drawings, 1 indicates the body of a vehicle; 2, the dashboard; 3, the seat; 4, the posts supporting the top rails 5, and 6 one of the cross-pieces connecting the rails 5.

7 refers to the body of the apron, and 8 to the front thereof, which when in use is extended over the top and down in front of the dashboard.

9 is a band securing the front of the apron to the dashboard. This band is bound in the central part of the front of the apron, as shown at 10, and the ends of said band are passed around the ends of the dashboard and buckled together behind the same at 11. The lower parts 12 of the front 8 of the apron are not secured to band 9, but are free therefrom and can be turned around the ends of the dashboard, so as to form part of the side flaps 13 of the apron, to which flaps the ends of front 8 are attached. Thus provision is made for using an apron with a dashboard shorter than that to which it was originally fitted.

To the upper corners of the body of the apron are fastened straps 14, having on their outer ends snap-hooks 15, adapted to engage guide-rods 16. These guide-rods are located a short distance from and parallel with top rails 5. At its inner end each guide-rod is turned downward and then toward the adjacent top rail and secured thereto, thus forming a shoulder 17. The outer end of each of the top rails is turned inward and parallel with cross-piece 6, as at 18, and then forward and fastened to said cross-piece 6, forming a shoulder 19.

When the inner end 20 of the apron is to be secured in a raised position, the snap-hooks are fastened to their respective guide-rods 16 and then pushed backward into engagement with the shoulders 17, or said hooks can be engaged directly with the shoulders. When it is desirable to open a side of the apron, the snap-hook on that side is moved along the guide-rod and engaged with the forward shoulder 19. The engagement of the snap-hooks with the shoulders prevents said hooks from being moved from their places by pres-

sure of wind or any accidental pressure, whereby the apron might be moved from the position in which it was placed. It will be observed that when one of the snap-hooks is 5 engaged with a forward shoulder 19 the curtain on that side of the vehicle is not only open for ingress and egress, but it also at the same time continues its protection of the seat, as shown in Fig. 2. The side flaps 13, 10 of the apron are held down by straps 21, buckled or otherwise detachably secured to the bottom of the body of the vehicle.

In Fig. 3 is illustrated the manner of securing the guide-rods and forming the shoulders 15 22 where it is necessary to attach the guide-rods to the under sides of the top rails. In this case the shoulders at the opposite ends of each guide-rod are formed alike.

Figs. 8 and 9 show the manner of binding 20 the edges of slot 23 in the body 7 of the apron, wherethrough pass the driving-reins 24, and the construction of the shield or hood 25 for said slot. Around the edges of said slot is placed a wire stiffener 26 for holding those 25 edges fully open, and said wire is embraced by a reinforce or binding 27, the sides whereof lap the edges of the slot and are sewed to the material of the apron and to each other, thus securing the wire in place. The ends of 30 shield 25 are connected with the body 7 of the apron by bellows-shaped ends 28, permitting the whole lower edge of the shield to be raised by the pressure of the driving-reins when drawn tight, thus allowing said reins to 35 be moved freely from side to side in the slot. The shield extends considerably below the slot, thus at all times preventing the entrance of rain, snow, or the like.

I do not confine myself to the shape or 40 manner of forming the shoulders for holding the snap-hooks in place, nor to the construction of other various parts herein shown and described, as it is obvious that many alterations may be made therein without departing 45 from the principle and scope of my invention.

Having thus described my invention, what I claim as new, and desire to secure by Letters Patent, is—

1. The combination, in a device of the 50 character described, of a storm-apron, a guide-rod having shoulders, and a device adapted to connect the apron with the guide-rod, said device engaging one of the shoulders of said rod to hold the apron in a closed position and to engage another shoulder thereof to hold said apron in an open position.

2. The combination, in a device of the 55 character described, of a storm-apron, a guide-rod having shoulders, and a device adapted to detachably connect the apron with the guide-rod, said device engaging one

of the shoulders of said rod to hold the apron in a closed position and to engage another shoulder thereof to hold said apron in an 65 open position.

3. The combination, in a device of the character described, of a storm-apron, guide-rods secured in the upper part of the vehicle and having shoulders formed on the ends 70 thereof, and hooks connected with the inner end of the storm-apron and attaching said apron to the guide-rods, said hooks being adapted to slide along the guide-rods and to engage the shoulders at either end thereof. 75

4. The combination, in a device of the character described, of a storm-apron, guide-rods secured to the upper rails of the top of the vehicle, shoulders formed on the front and back ends of the guide-rods, and snap-hooks adjustably connected with the inner end of the storm-apron, said hooks taking 80 around the guide-rods and being adapted to slide thereon and to engage the shoulders at the ends thereof.

5. The combination, in a device of the character described, of a storm-apron, guide-rods parallel with and secured to the upper rails of the top of the vehicle, shoulders formed on the front and back ends of the 90 guide-rods, straps on the inner end of the apron, and snap-hooks adjustably connected with said straps, said hooks taking around the guide-rods and being adapted to slide thereon and to engage the shoulders on the 95 ends thereof.

6. The combination, in a device of the character described, of the dashboard, a storm-apron having the front thereof lapping the front of the dashboard, a band bound in 100 the central part of the front of the apron, the ends of the front of the apron being free from the band, means for securing the ends of the band on the inner side of the dashboard, guide-rods parallel with and secured to the 105 upper rails of the top of the vehicle, shoulders formed on the ends of the guide-rods, straps on the inner end of the apron, snap-hooks adjustably connected with said straps, said hooks taking around the guide-rods and being adapted to slide thereon and to engage the shoulders on the ends thereof, side flaps on the 110 apron, and means for detachably securing the flaps to the lower part of the body of the vehicle.

7. The combination, with a storm-apron of the character described having a slot wherethrough the driving-reins may pass, of a shield having its upper edge secured to the storm-apron above the slot and covering 120 said slot, and bellows-shaped ends on the shield and connecting the ends of the shield with the said apron.

8. The combination, with a storm-apron

of the character described having a slot | slot, and bellows-shaped ends on the shield
